Filed Aug. 12, 1969, Ser. No. 18,654

Term of patent 14 years

Int. Cl. D8—03

U.S. Cl. D8—271

FIG. 1

FIG. 2

FIG. 1 is a front plan view of the fluted nail;

FIG. 2 is a top view thereof; and

FIG. 3 is a bottom view thereof.

The sides and back, not shown, are identical to the view shown in FIG. 1.

The characteristic feature of the fluted nail of this invention lies in the twisted flanges of the fluted nail with each of the flanges having side to side undulations therein.

We claim:

The ornamental design for a fluted nail, as shown and described.
